MACHINE FOR CLOSING AND POSITIONING
SPRINGS IN POCKETSFrederick F. Zeier, Nyack, N. Y., assignor to
Metropolitan Sewing Machine Corporation,
Nyack, N. Y., a corporation of Delaware

Application February 10, 1934, Serial No. 710,657

11 Claims. (Cl. 112—2)

The present invention relates to a novel and improved machine for closing and positioning springs in pocketed strips.

One of the objects of the present invention is to provide an economical yet highly efficient machine for closing the open side of pocketed strips containing contra-axially disposed springs in the pockets thereof, and for moving the coil springs from the contra-axial to an axial position in the pockets of the strip.

It is another object of the present invention to provide a machine for turning springs in a pocketed strip which will not tear or wear the strip.

All efforts in this direction heretofore have resulted in very large, cumbersome, costly and therefore impractical machines. The present invention, however, provides a compact, economical and highly efficient machine which is extremely practical, and which, in addition to providing a new structure and mode of operation for a spring turning device, provides other instrumentalities in the unitary structure which operate coordinately with the pocket closing element for performing additional operations on the loaded strip to improve the quality and speed the output.

One feature of the present invention is the provision of a structure adapted to move contra-axially disposed coil springs in a proper transverse plane relative to the pockets in the strip.

Another feature is the provision of means adapted to straighten out the free lips of the fabric strip prior to operation thereon by the sewing mechanism.

A still further feature of the present invention is the provision of a device adapted to pink the side of the fabric strip associated with and functioning coordinately with other operating parts of the machine.

Yet another feature is the provision of a novel main conveyor adapted to both compress the coil springs within the fabric strip and to advance the loaded strip in a positive manner, which may be used either separately or in conjunction with a puller feed mechanism.

A still further feature of the present invention is the provision of a novel spring turning apparatus which embodies a new mode of operation having the characteristic of being positive in its action and preventing wear and tear on the fabric strip. In addition, too, the present invention embodies the feature of accommodating various sizes of both strips and coil springs without any changes in the structural parts of the machine. Other features and advantages will hereinafter appear.

In the drawings:

Figure 1 is a front elevation.

Fig. 2 is a side view.

Fig. 3 is a perspective view of the fabric strip in various stages of completion. 5

Fig. 4 is a detached side view of the guide.

Figs. 5, 6, and 7 are sectional views of the housing taken on lines and arrows 5, 6, and 7, respectively, in Fig. 1.

Fig. 8 is a top view of the pincer detail. 10

Fig. 9 is a side view of the pincer.

Fig. 10 is a detached view of the puller feed mechanism.

Fig. 11 is a detail view of the fabric straightening plate. 15

Fig. 12 is a fragmentary top plan view.

Before proceeding with a detailed description of the various structural details and mode of operation of the present invention, it is desirable that brief reference be made to the various functions accomplished by it. This may be understood best by viewing Fig. 3 wherein there is shown a pocketed fabric strip 12 comprising a woven strip having an upper ply 13 and lower ply 14 with a closed side 15 and open side 16 20 to the strip, and having evenly spaced walls 17 dividing the strip into a series of pockets 18 throughout its length. Preferably, though not necessarily, the dividing walls 17 end somewhat short of the outer edge of the open side 16 forming a free upper lip 13' and a free lower lip 14' for the purpose of facilitating original contra-axial entrance and assembly of coil springs 19 30 into individual pockets. The present invention is equally operative and advantageous on strips 35 formed by merely folding one ply on another and by stitching partly or fully thereacross to form pockets.

In its broadest embodiment, the machine of the present invention functions: first, to flatten 40 the springs 19 in the contra-axial position in the pockets 18; second, to guide the loaded strip 12 to a main conveyor 20; third, to straighten the upper and lower free lips 13' and 14' respectively; fourth, to pink the open side 16 of the strip; fifth, to compress, hold and feed the pocketed springs to a plurality of stations for various operations thereon; sixth, to close the pockets; seventh, to pull the fabric in synchronism with the pocket closing element and with the main conveyor; eighth, to move the springs from a contra-axial into an axial position within the closed pocket. If preferred, in some embodiments the third and fourth functions, for example, may be eliminated. 50 55

Considering these multifarious functions, the present invention provides a comparatively simple, economical, yet very satisfactory and highly efficient machine. This will be appreciated when it is realized that in practice the operator practically allows the machine to run itself and may direct practically all his attention to the manual operation of sliding the pockets 18 onto the inserter-nozzle of a nearby inserter mechanism (not shown) and loading springs 19 therein, and steps on a pedal 22 to stop the machine of the present invention for a moment or two if it should happen to use up the ordinary intermediate surplusage of loaded strip at the introductory side thereof.

Structural details of the present invention, in the form now preferred, comprise a main base 23 supported in spaced relation to a floor by suitable legs 24, adapted to support a sewing head 25 which may, as shown, be a conventional and well-known Metropolitan type sewing machine passing threads 26 and 27 to a needle 28 and a looper respectively in the conventional manner and providing a usual presser foot 29 and feed dog 30. This sewing machine makes a line of stitching 31 to close the open side 16 as the fabric strip is moved to it in a manner about to be described.

At the entrance side of the machine the present invention provides a guide 32 including a table 33 or support preferably with a curved top 33' secured as by arms 34 on a shaft 35 to blocks 36 on long standards 37 with an inverted, U-shaped shell 38. As may be seen best in Figs. 1, 35 and 4, the guide further includes a free roller 39 on arms 40 secured to the base 23 by screws 40' overlying the table to initially compress the springs and to align them transversely in a contra-axial position in the pockets 18 as the strip 12 is drawn across the table. The inverted, U-shaped shell also serves to align the springs transversely, but mainly it guides the loaded fabric strip properly depthwise of the machine, relative to the sewing machine head 25 and to the novel form of main conveyor 20.

The main conveyor comprises an endless lower belt 41 operating below the base 23 over free running pulleys 42 and 43 on shafts 44 and 45 and above the base over a free pulley 46 on the shaft 35 at the entrance side of the machine, and over a traction or driver pulley 47 on a shaft 48 near the outlet side of the machine. The shafts 35 and 48 are supported in blocks 36 and 49 for adjustment in the long standards 37 and short standards 50 respectively to be adjustably fixed at the proper vertical plane relative to a table 51 of the sewing head 25 and to other operating units. The shafts 44 and 45 of the lower free pulleys 42 and 43 are similarly mounted in slide blocks 52 and 53 for vertical adjustment on lower standards 54 and 55 respectively, the adjustment being provided to initially tighten the endless belt 41 on the driver pulley 47 and to take up slack as the belt stretches.

A complementary upper endless belt 56 is provided, to run in unison with the lower belt 41, operating over a free running pulley 57 on a shaft 58 at the entrance side and over a driver pulley 59 on a shaft 60 at the outlet side of the machine.

The shaft 58 of the free running pulley 57 is supported in blocks 61 for vertical adjustment on the long standards 37 where they are secured in desired position as by a set screw 61'. Straps 75 62 secured to the blocks 61 with screws 63 are

provided with a vertical bent section 62' having elongated slots 63 to accommodate holding screws 64 and are slidable vertically on the side of the sewing machine head 25 in order to brace the upper ends of the long standards 37 in any set position of the blocks. The shaft 60 of the driver pulley 59 is similarly mounted in adjustment blocks 65 on the double short standard 50, and is adjustable thereon in order to provide any desired spacing in the work supporting area between the upper and lower belts 41 and 56. A set of straps 66 similar to the straps 62 are secured to the slide blocks 65 at their lower ends, and are provided with a screw and elongated slot connection 67 on the side of a puller feed mechanism 68 (similar to 63 and 64) to support the blocks in the desired vertical position and to brace the free end of the short standard 50.

As is shown most clearly in Fig. 1, the free running pulley 57 of the upper belt 56 is on a higher plane vertically than the driver pulley 59, and a frame 69 rotatably supporting a plurality of rollers 70 on pins 71 is provided to guide the belt through an angular path 72 and then through a substantially parallel path relative to the upper run of the lower belt. This frame is supported by upwardly extending straps 73 and 74, having screw and elongated slot connections 73' and 74' on the straps 62 and 66 for adjustability.

While the coil springs 19 are in an unrestrained, expanded, contra-axial position in the individual pockets, they tend to pull back the open side of the strip midway between the dividing walls 17. However, the main conveyor, in addition to feeding the loaded strip to the sewing machine needle and to other stations, serves to compress the spring in the contra-axial position so that the open side of the strip remains substantially parallel and so that the line of stitching is parallel with the side thereof. The angular incline 72 of the belt gradually compresses the spring just prior to its entrance into the parallel area between the two belts.

This main conveyor 20 alone may be used to move the loaded strip to the various operating stations, but in order to insure a more satisfactory result the present invention provides a puller feed mechanism 68 on a plane with the outer or open side of the strip and substantially central with the travel of the work relative to the needle. The puller feed mechanism may be of a conventional type, for example, and as shown, the well known Metropolitan puller feed mechanism comprising a main frame 68 with a lower feed roller 75 on one end of a drive shaft 76 extending through the frame, and an upper feed roller 77 mounted on a shaft 77' in a yoke 78 for limited vertical movement in an overhanging arm portion of the frame. Rotation of the lower feed roller is accomplished through the provision of a clutch 79 intermittently operated in a uni-directional movement by an arm 80 connected to an eccentric 81 on the end of a main drive shaft 82 of the sewing machine, and the upper feed roll is driven in unison with the lower feed roller through meshing gears 83 and 84 connected to the shafts 76 and 77' respectively. The lower shaft 76 is provided with a small sprocket 85 adapted to drive a large sprocket 86 on the driver pulley 47 through a chain 86', and the coordinately rotating shaft 77' of the upper feed roll is provided with a similar small sprocket 87 for moving a large sprocket 88 on the upper driver pulley through a chain 88'. 75

The ratio between the small sprockets and large sprockets is proportioned to impart the same peripheral speed or movement to the face of the driver pulleys 47 and 59, and to the puller feed rollers 75 and 77. The eccentric 81 and clutch 79 are adjusted to rotate the puller roll shaft 76 in proper speed and travel with the usual feed dog and reciprocation of the needle 28 while the latter two are operated by the main drive shaft 10 of the sewing machine head 25 in the usual manner. Thus, there is absolute synchronized travel between the main conveyor 20, the feed dog 30 and the puller feed 68.

This strip advancing mechanism comprising the main conveyor 20 and/or the puller feed 68 of the present invention is intended to be used not alone for advancing the strip to the needle for the line of stitching, but advances it to a plurality of other stations to be worked upon by other mechanisms.

One of these other stations includes a fabric straightening device including a finger plate 89 secured to the standard 37 with a yoke 89' and adapted to enter between the free lips of the fabric to straighten out either or both the upper lip 13' and the lower lip 14' if either should happen to be curled in from the spring inserting operation; and also includes a belt 90 on a free running upper pulley 91 supported in a standard 91' and running around a lower pulley 92 secured to a lower drive shaft 93, which is adapted to sweep against the underside and straighten out the lower lip should it happen to be curled back on the outside of the fabric strip. In those cases where a strip with dividing walls extending to the outermost edge of the open side is used, so that the dividing walls would hook onto the finger plate 89, it is merely necessary to loosen the yoke on the standard 37 and swing it out of operative position relative to the strip.

At another station, preferably intermediate the straightening device 89 and sewing mechanism 25, the present invention is provided with a pinking device 94 (see Figs. 8 and 9) adapted to cut a serrated edge 96' on the open side 16 of the strip 12 to prevent unravelling of long lengths of the warp which would otherwise curl around the feed dog and other operating parts of the machine and cause trouble. When the open side of the fabric is provided with a selvage this trouble would not occur and it would not be necessary to use the pinker. Various types of pinkers may be used in the combination of the present invention, but because of its simplicity, long life, and ease of operation, a slight modification of the well-known Metropolitan pinker is used, as is shown most clearly in Figs. 8 and 9. It comprises a base member 95 supporting a zigzag cutting roll 96 for uni-directional rotation on a shaft 97 and having a uni-directional clutch 98 with an arm 98' providing an adjustable connection 99 with a connecting rod 100 associated at its opposite end with an eccentric 101 on the forward end of the main drive shaft 82. A yoke 102 having a pivotal connection on a pin 103 supports a pressure roller 104 on a stud 105 at its outer end, while a stud 106 secured to the base member 95 and passing through a hole in the yoke above which it is provided with a coil spring 107 and wing nut 108 is adapted to alter pressure of the roller.

The pinker 94 is not shown fully in the plan views since it is used only sometimes, and because it would confuse the other details. However, it is shown there by dot and dash lines 109, 75 for it is merely necessary to take the device

shown in Figs. 8 and 9 and secure it to the main base of the machine with screws 110 in the tapped holes 111 shown clearly in Fig. 1. By proper adjustment of the connection 99 the peripheral speed of the cutter wheel is in the same ratio as the main conveyor 20, feed dog 30, and puller feed 68.

The final station to which the main conveyor 20 and puller feed 68 of the present invention moves the loaded fabric strip is a spring turning, or positioning device 112 at the outlet side of the machine which is of particularly novel construction and represents a new mode of operation for devices of this character. It embodies a table 113 suitably secured to the base 23 that supports a housing 114 adapted to substantially enclose the fabric strip 12 as it is fed from the machine and to support one side of the loaded fabric strip while a unidirectional spring turning instrumentality 115 in the form of beater straps 20 operates on the other side to turn the spring.

The housing is provided with an entrance 116 shaped substantially as shown in Fig. 5 and aligned with the loaded fabric strip as it comes from the main conveyor 20. In the middle section it is preferably shaped as shown in Fig. 6, including a centrally disposed convexity 117 and receding concavity 118, and has an outlet 119 preferably as shown in Fig. 7. The underside of the table 113 is hollowed out and has a cut-out 113' underlying the middle section of the housing 114 in order to permit the beater strap 115 to engage the loaded fabric.

The straps are preferably secured to cross pins 120 on a hub 121 mounted on the outer end of an operating shaft 93. The straps may have metal clips 122 secured to the ends thereof by rivets 123 in order to lessen wear and to impose a hammer-like impact upon the springs.

As the loaded fabric 12 with the contra-axially disposed springs 19 is fed to the housing 114, subsequently to the closing thereof by the line of stitching 31, the beater straps 115 which are rotated at a fairly high speed, initially engage the contra-axially disposed springs, as shown in Fig. 5, and cause the spring to begin to move toward the axial position in the pocket, and subsequent blows by the beater straps cause it to move into the full axial position (shown in Fig. 6) wherein the jumping of the spring into the axial position is facilitated by the centrally disposed convexity 117 and the concavity 118 extending therefrom. Figure 6 also shows the fabric out of a transverse plane which is caused by the spring as it quickly expands into the axial position within the 55 pocket.

The upper part of the tunnel or housing designated as the convexity 117 causes a retarding in the feeding of the strip by slightly holding back the previously opened spring in the pocket, which in turn provides an automatic positioning of the spring to be opened and gives the beater sufficient time to turn the spring in the pocket. The length of the tunnel or housing is approximately twice the diameter of the coil spring.

The pin connection 120 on the hub 121 which provides a free pivotal connection for the straps 115 so that they travel in extended position by centrifugal force, allows the straps to yield or lay back if the spring should be caught in the 70 pocket 18, and the curved walls 117 and 118 facilitate turning the springs. Thus, either or both these structures overcome wear and tear on the fabric strip. Further, the travelling instrumentality 115 working in one direction on only one 75

side of the strip causes less pull and strain on the fabric than some previous proposals working and travelling on two sides of the strip.

Movement of the fabric through an equivalent 5 90 degrees while turning the spring from the contra-axial into the axial position is prevented by general holding of the loaded strip by the main conveyor 20 and puller feed 68, and by the axially disposed springs sliding upon the angular 10 facing 124 of the table 113.

Operation of the complete machine is preferably accomplished with a single electric motor 125 or other prime mover below the machine connected to a source of power 126 having a 15 switch 127 and cord 128 adapted to drive a belt 131 extending to a main drive pulley 132 on the end of the main drive shaft 82 on the sewing machine 25, and a second pulley 133 adapted to drive a second belt 134 to an intermediate pulley 20 135 on an intermediate shaft 136 mounted on a set of double standards 137 and drive an intermediate belt 138 from a small pulley 138' on the intermediate shaft to a large pulley 139 on the drive shaft 93. This latter shaft operates the 25 fabric straightening belt 90 and the beater straps 115 in the manner hereinbefore described. Thus, the one prime mover through the belt 131 is adapted to operate the feeding dog 30 and reciprocate the needle 28 in the sewing head, and 30 through the main drive shaft 82 thereof operates the eccentric 101 on the forward end to drive the connecting rod 100 and impart uni-directional movement to the pincer 94, and through the eccentric 81 on the rear end thereof operates the 35 connecting rod 80 to impart unidirectional movement to the set of feed rolls 75 and 77 and to the interconnected main conveyor 20, while the second belt 134 drives the intermediate belt 138 and shaft 93 to straighten the fabric with the belt 40 90, and to change the position of the springs 19 within the pockets 18 with the beater straps 115.

A slip clutch 140 is provided intermediate the 45 pulley 129 and the armature shaft 141 in order to quickly break the driving connection and to quickly start it again by merely stepping on the pedal 22. A suitable linkage 142 is provided between the pedal 22 and clutch 140 to intermittently start and stop operation. The speed of 50 the machine is adjustable with the slip clutch from a minimum or zero to maximum by the foot pedal control which can be moved at the will of the operator, and gives the operator an opportunity to either speed up the work of the sewing 55 unit or slacken it down as the occasion demands.

In using the machine of the present invention the following steps occur: the woven fabric strip 12 or an otherwise formed pocketed strip has coil 60 springs 19 inserted in each of the pockets 18 in contra-axial position, either by hand or by one of the now well-known spring inserting machines to build up a considerable surplusage of loaded strip, and then the leading edge of the loaded 65 strip is passed onto the table 33, thence under the roller 39 and through the guide 38 to be straightened and guided thereby to the other main operating parts. Next the leading edge is moved onto the top run of the lower belt 41 and 70 under the angular stretch 72 of the upper belt 56 to be gradually compressed by the angular run 72, and into the confining area between the two belts, thence running, by slow power if preferred, to the sewing mechanism 25 and to the 75 puller feed mechanism 68, and subsequently to

the spring turning device 112 as the strip passes from the outlet side of the machine.

The upper puller feed roll 77 may be lifted while starting the strip through stepping upon and actuating a pedal 143 and chain 144 connection 5 with a conventional lever lift (not shown) connected to the roller yoke 78. The open side 16 of the strip may be led over the straightening place 89 and onto the pincer device 94 as the strip is initially passed to the main conveyor 20, or these 10 latter two devices may be moved into operative position after the leading edge of the loaded strip has passed through the entire machine.

When the strip is properly started and the motor actuated by closing the switch 127, it is 15 merely necessary to step on the clutch pedal 22 in order to cause the machine of the present invention to successfully and in combination perform the various operations hereinbefore described in detail; viz, straighten the springs in 20 the pockets, guide the loaded strip, straighten the lips, trim the open side thereof, form a line of stitching, and then with the novel spring turning instrumentality of the present invention change the spring from a contra-axial to the 25 axial position in the individual pockets. The feeding elements are so positive, and the co-action of the function performing parts so satisfactory, that output of the present machine is limited only by the speed of the preparatory coil 30 winding and inserting machines.

Operative parts of the conveyor belts 41 and 56 are located under the arm of the sewing machine and arm of the puller feed mechanism 68, which is a great help to make the machine and 35 the installation very compact. In other words, the strips loaded with springs pass to the right of the line of stitching as viewed in Fig. 2, which helps to keep the strips under better control relative to the sewing.

The structure of the present invention is so arranged that it accommodates pockets of various 40 lengths and coils of various diameters. To this end the guide 38 is made with a loose part 38' (see Fig. 4) adjustable in width through the 45 provision of tongues 146 on the loose part adapted to hook into the apertures 145 in the top face of the table 33 and to be locked in the desired set of slots for the various widths when a wing nut 147 secures the two guide parts 38 and 38' 50 together.

The relationship of the open side of the strip is always the same in connection with the needle and puller feed, and consequently the rear plate, 38' of the guide 38 is the only one that need be 55 changed. As pointed out hereinbefore, the upper belt 56 of the main conveyor 20 may be raised or lowered to accommodate contra-axially disposed springs of greater or less length.

Similarly, the housing 114 of the spring turning device 112 is adapted to be adjusted for 60 springs of various lengths by the provision of an interfitting connection 149 including a recess 150 in the housing part 151 adapted to receive a tongue 152 on the other part 151' of the housing, 65 and a slot 153 on the tongue adapted to receive a key 154 on the convex member 117. A stud 155 on the latter member passing through elongated slots 156 and 157 locks the various parts together when a wing nut 158 is tightened. The housing 70 is also adjustable in height to accommodate various diameter springs by the provision of substantially L-shaped straps 159 with fingers 160 adapted to enter any one of a plurality of vertically spaced notches 161 to support the hous- 75

ing at various heights relative to the table 113, and provided with elongated slots 162 and screws 163 in feet 164 thereof to hold the housing to the table in its various widths and heights.

5 Variations and modifications may be made within the scope of the present invention, and portions of the improvements may be used without others.

I claim:

10 1. In a machine for closing a pocketed strip with coil springs in the pockets thereof, the combination of a sewing head; a pair of endless belts adapted to compress the springs in the pockets and to advance the strip to the sewing head; a support at the entrance side of the machine over which the loaded strip passes to the pair of endless belts; and an inverted U shape shell associated with the support adapted to align the springs relative to the pockets and strip prior to 20 compression thereof by the endless belts.

15 2. In a machine for closing a pocketed strip of fabric having an open side with an upper and a lower free lip, and having coil springs in the individual pockets thereof, the combination of a 25 sewing head; means for directing and moving the open side and free lips of the pocketed strip with coil springs to the sewing head, to be closed thereby; a plate adapted to straighten the upper free lip; and a driven belt adapted to straighten 30 the lower free lip, prior to operation on the strip by the sewing head.

30 3. In a machine for closing a pocketed strip of fabric having an open side with free lips and coil springs in the individual pockets thereof, the 35 combination of a pocket closing element; means for directing and moving the open side and free lips of the strip to the pocket closing element; and means adapted to positively move the free lips from an improper folded back position to a proper flat position prior to the operation thereon 40 by the pocket closing element.

40 4. In a machine for closing a pocketed strip with coil springs contra-axially disposed in the individual pockets thereof, the combination of a 45 sewing head; a pair of endless belts for conveying the loaded strip to the sewing head; and a roller frame adapted to impart an angular and parallel run to one belt relative to the other belt for first partially compressing and then fully compressing the spring in the pocketed strip.

50 5. In a machine for closing a pocketed strip with coil springs contra-axially disposed in the individual pockets thereof, the combination of a sewing head; a pair of endless belts for conveying the loaded strip to the sewing head; a

5 roller frame adapted to impart an angular and parallel run to one belt relative to the other belt for first partially compressing and for then fully compressing the spring in the pocketed strip; and means adapted to support the upper belt and roller frame in various planes and heights relative to the other belt.

6. An instrumentality for turning coil springs in the pockets of a strip, comprising a stationary 10 housing having a substantially rectangular opening adapted to receive the spring loaded strip; moving means cooperating with said housing to turn the coil springs from a contra-axial into an axial position in the pockets; and means for enlarging the opening in said housing both vertically and horizontally to accommodate various 15 sizes of strips and coil springs.

7. An instrumentality for turning coil springs in the pockets of a strip, comprising a stationary 20 housing adapted to receive the spring loaded strip; curved walls within said housing; and moving means cooperating with said curved walls within the housing to turn the coil springs from a contra-axial into an axial position in the 25 pockets.

8. In a machine for turning coiled springs in a pocketed strip, the combination of a housing adapted to receive said pocketed strip; and a beater mechanism cooperating with said housing to turn the springs from a contra-axial to an 30 axial position within the individual pockets of the strip.

9. In a machine for turning coiled springs in a pocketed strip, the combination of a housing 35 adapted to receive said pocketed strip; a conveyor for advancing the loaded pocketed strip to the housing; and a beater mechanism cooperating with said housing to turn the springs from a contra-axial to an axial position within 40 the individual pockets of the strip.

10. In a machine for turning coiled springs in a pocketed strip, the combination of a housing adapted to receive said pocketed strip; and means cooperating with said housing to turn the springs from a contra-axial into an axial position within 45 the individual pockets of the strip.

11. In a machine for turning coiled springs in a pocketed strip, the combination of a housing 50 adapted to receive said pocketed strip; a conveyor for advancing the loaded pocketed strip to the housing; and means cooperating with said housing to turn the springs from a contra-axial into an axial position within the individual pockets of the strip.

FREDERICK F. ZEIER. 55
